Primary Examiner — Cynthia Underwood*(74) Attorney, Agent, or Firm* — DWC Law Firm, P.S.; David Chen(57) CLAIM

The ornamental design for a tablet case, as shown and described.

DESCRIPTION

FIG. 1 is a bottom perspective view of the tablet case of the present invention.

FIG. 2 is a top plan view of the tablet case of FIG. 1.

FIG. 3 is a bottom plan view of the tablet case of FIG. 1.

FIG. 4 is front side elevation view of the tablet case of FIG. 1.

FIG. 5 is back side elevation view of the tablet case of FIG. 1.

FIG. 6 is right side elevation view of the tablet case of FIG. 1; and,
